UNITED STATES PATENT OFFICE

LOUIS WILPUTTE, OF NEW ROCHELLE, NEW YORK, ASSIGNOR, BY MESNE ASSIGNMENTS, TO WILPUTTE COKE OVEN CORPORATION, OF NEW YORK, N. Y., A CORPORATION OF MAINE

COKE-OVEN DOOR

Application filed July 11, 1924. Serial No. 725,333.

My present invention consists in an improvement in coke oven doors of the so-called plug type employed for closing the ends of the horizontally elongated coking chambers of modern by-products coke ovens. The general object of the invention is to provide a door of the kind specified, characterized by its mechanical simplicity and durability and by the special provisions made for restricting the heat radiation from the outer surface of the door, such radiation of heat being especially objectionable not only because of the heat loss involved, but because it subjects to discomfort and impairs the efficiency of the attendants who have to work on the benches or portions of the coke oven structure in front of the door.

The various features of novelty which characterize my invention are pointed out with particularity in the claim annexed to and forming a part of this specification. For a better understanding of the invention, however, and the advantages possessed by it, reference should be had to the accompanying drawings and descriptive matter in which I have illustrated and described a preferred embodiment of the invention.

Of the drawings:

Fig. 1 is an elevation of one form of door; Fig. 2 is a section on the line 2—2 of Fig. 1; Fig. 3 is a section on the line 3—3 of Fig. 1; Fig. 4 is a view taken similarly to Fig. 2 showing a modified door construction; and Fig. 5 is a section on the line 5—5 of Fig. 4.

In the drawings, and referring first to the construction shown in Figs. 1, 2, and 3, A represents the cast iron or steel body or frame of the door. The frame part A comprises the usual inner rim or flange A' at the inner side of a connecting web A². The flange A' runs all around the margin of the door and is undercut and serves to hold in place the usual fire brick lining B. At the outer side of the web A², the door frame part A is provided with outwardly projecting flanges A³ which form the sides of a heat insulating space. As shown, the heat insulating space

surrounded by the ribs A³, is formed in three sections, the middle section being separated from the upper and lower sections by spaces in which are located the provisions D and E, respectively, for engagement by the door handling machine. Each section of the heat insulating space is closed at its outer side by a corresponding cover plate C which may well be a comparatively thin plate of metal riveted or bolted to the flanges A³. Preferably, each section of the heat insulating space between the door body web A² and the corresponding web section C is filled with a light weight material F having high heat insulating properties, which may well be in the form of Sil-o-cel blocks or the like.

In lieu of employing a metallic door body A having a continuous web A² between the fire brick lining B and outer heat insulating space, I may use the type of door body member AA as shown in Figs. 4 and 5, in which the integral web portion A²⁰ is largely cut away to reduce casting strains and the liability of the member AA warping and cracking in service. The openings A²¹ formed in the web A³ by thus cutting away the web are closed by a steel plate A²² riveted to the body part AA at the margin of the opening.

With either form of the invention illustrated, the heat radiation from the outer surface of the door is much less than with coke oven doors now in use, and this advantage is obtained without material increase in the weight or cost of construction of the door. The importance of reducing the heat radiation from the coke oven doors to reduce heat waste, and to protect the oven attendants will be readily understood when account is taken of the fact that the inner side of such a door is subjected to a temperature which ordinarily is in excess of 2000° F., and that in removing and replacing the door, luting the latter, and in other operations, it is necessary for the oven attendants to work in front of and in close proximity to the doors.

An important and distinguishing characteristic of the invention is the provision of the gas tight wall formed by the integral web A² of Figs. 1 and 2, and by the cut away web A²⁰ and cover plate A²² of Figs. 3 and 4,

between the fire brick door B lining and the heat insulating space. This not only prevents the leakage of gases into the heat insulating space, but prevents the collection 5 of tar in such space which would otherwise interfere with its heat insulating properties, and in particular would impair the effectiveness of the Sil-o-cel or like packing which I consider practically essential to the full realization of the advantages of my invention.

10 Having now described my invention, what I claim as new and desire to secure by Letters Patent, is:

15 A coke oven door comprising a metallic frame formed with a gas tight web portion, a fire brick lining mounted in said frame at one side of said web portion, means cooperating with said web portion to form a plurality of spaced closed heat insulating 20 compartments of low heat conducting capacity on the opposite side of said web portion and spaced from each other in a direction parallel to said web portion and means located on said web portion between said compartments by which said door may be mechanically moved.

25 Signed at New York city in the county of New York and State of New York this 9th day of July, A. D. 1924.

30 LOUIS WILPUTTE.
